S. PALHEGYI & H. EICHNER,

WELL PUMP.

APPLICATION FILED MAY 11, 1917, RENEWED AUG. 14, 1918.

1,279,899.

Patented Sept. 24, 1918.

FIG. 5.

A. M. Wilson.
Attorney

UNITED STATES PATENT OFFICE.

STEPHEN PALHEGYI AND HERMAN EICHNER, OF DETROIT, MICHIGAN.

WELL-PUMP.

1,279,899.

Specification of Letters Patent. Patented Sept. 24, 1918.

Application filed May 11, 1917, Serial No. 168,001. Renewed August 14, 1918. Serial No. 249,884.

To all whom it may concern:

Be it known that we, (1) STEPHEN PALHEGYI and (2) HERMAN EICHNER, (1) a subject of the King of Hungary, and (2) a citizen of the United States, residing at Detroit, in the county of Wayne and State of Michigan, have invented certain new and useful Improvements in Well-Pumps, of which the following is a specification.

10 This invention relates to certain new and useful improvements in well pumps.

The primary object of the invention is to provide a pump that is semi-automatic in operation, as by the weight of the piston 15 within the well pump elevating the water to a desired height.

A further object of the invention is to provide a well pump in which the weight and gravity of the piston contained therein 20 are utilized to elevate a small column of water, with manually operated means for elevating the piston when the same has reached the lower limit of its movement, as well as embodying means for arresting 25 movement of the piston at any time.

With these general objects in view and others that will appear as the nature of the invention is better understood, the same consists in the novel construction, combination 30 and arrangement of parts hereinafter more fully described, illustrated in the accompanying drawings, and then claimed.

In the drawings forming a part of this application and in which like designating 35 characters refer to corresponding parts throughout the several views:—

Figure 1 is a vertical sectional view of a well pump constructed in accordance with the present invention, showing the pump 40 cylinder and piston at the lower end of the well, as well as the rack and pinion mechanism at the upper end of the well for controlling movement of the piston.

Fig. 2 is a horizontal sectional view on 45 line II—II of Fig. 1.

Fig. 3 is a horizontal sectional view on line III—III of Fig. 1 showing the mechanism for arresting the movement of the piston.

50 Fig. 4 is a diagrammatic view of a portion of a house showing the present well pump operatively arranged relative thereto, and,

Fig. 5 is a detail view of the releasing 55 mechanism for the pump piston as embodied in Fig. 4.

Referring more in detail to the accompanying drawing and particularly to Fig. 1, the reference numeral 10 designates a well sunk into the ground of any desired depth and lateral dimensions and having positioned therein a cylindrical filtering porous lining 11 as clearly shown in Figs. 1 and 2, the lower portion of the lining 11 having desired portions as 12, varied in construction to receive a change of filtering material as gravel or charcoal as may be desired. As is indicated, the lining 11 may be formed of cylindrical sections having co-operating adjacent engaging faces so as to 70 prevent the entrance of water into the well without first being filtered.

The pump mechanism arranged within the well includes a cylinder 13 having a closed bottom 14 resting upon supports 15 75 as indicated in Fig. 1 while the lower end 14 of the cylinder 13 is provided with a plurality of upwardly opening flap valves 16 operating in a manner presently to appear. The cylinder 13 at its upper end is held 80 spaced from the side walls of the lining 11 by brackets 17 more clearly shown in Fig. 2.

The piston associated with the cylinder 13 includes a head 18 carried by the piston rod 19 and held rigidly thereto by the inclined braces 20, the piston 18 being limited in its upward movement by the circular band 21 fixed to the inner upper edge of the cylinder 13 and projecting inwardly thereof as is shown in Fig. 1.

A rack bar 22 is fixed to the upper end of the piston rod 19 and projects upwardly through a central opening 23 provided in the well cover 24, the rack bar 22 being inclosed by the housing 25 supported on the well 95 cover 24 and as shown in Fig. 1, extends upwardly into the housing tower 26 whereby access may be had to the upper end thereof by the hinged cover 27 upon the said tower, the same being also viewable through the side opening 28. A pair of guides 29 is fixed to the rear wall of the housing 25 and engages opposite sides of the rack bar as is shown in Fig. 3 to hold the same properly positioned at all times while roller bearings 105 30 are journaled in the side walls of the housing and engage the rear face of the rack bar as is also clearly illustrated.

The mechanism for raising and lowering the rack bar, and consequently the piston 110 head 18, includes a pair of vertical standards 31 supported upon the well cover 24 within

the housing 25 and having journaled in said standards a pair of shafts 32 and 33 upon which are journaled meshing pinions 34 and 35, the pinion 35 meshing with the rack bar 22. A crank handle 36 is fixed to the shaft 32 and when rotated, similar motion is communicated between the meshing gears 34 and 35, and in turn, the rack bar and piston carried thereby are reciprocated in vertical directions as is plainly evident. In order to hold the piston and rack bar in any desired position, a bracket 36 is carried by the front wall of the housing 25 and has slidably mounted therein, a rod 37 tensioned for forward sliding movement as at 38 and provided with a toothed head 39 for engagement with the gear wheel 34, the same being released therefrom against the tension of the spring 38 by pulling outwardly upon the operating handle 40.

When it is desired to elevate water from the well 19 with the piston 18 at substantially the limit of its lower movement, the said piston is elevated by the above described mechanism and upon such movement, the water filtered through the lining 11 will be drawn into the cylinder 13 by way of the upwardly opening flap valves 16, and when the piston stops such upward movement, the water contained within the cylinder 13 by its weight will close the flap valves 16 and such water will be retained within the cylinder. By releasing the toothed head 39 from the pinion 34, the descending movement of the piston 18 increased by the desired weight will force the water out of the cylinder 13 at the lower end thereof by way of the stand pipe 41 supported by brackets 42 to the upper end thereof, at which point a discharge nozzle 43 receives the water from the stand pipe 41 and delivers the same in the usual manner of a pump. It will be understood that the pumping of the water may be instantly stopped by permitting the toothed head 39 of the tensioned sliding bar 37 to engage the pinion 34 and subsequently arresting the lowering movement of the rack bar 22 and the piston 18 carried thereby.

Figs. 4 and 5 show diagrammatic views of the present system embodied in a house wherein a flexible connection —a— extends from the rod handle 40 over a pulley —b— to continue to different points or terminals as at —c—. Each floor —d— of the structure —e— is provided with a water supply —f—. When it is desired to draw water from the supply —f—, the terminals —c— embodying a rotatable shaft —g— journaled and slidably mounted upon the shaft —h— fixed in the structure —e— and having connected thereto the flexible member —a—, rotation of the shaft —g— will wind the flexible member —a— thereon and accordingly disengage the toothed head 39 from the rack bar and permit the water to flow upwardly

by way of the supply line —i— to the members —f—. The supply may be continuous by holding the toothed head removed from the pinion 34 and subsequently holding the cylinder —g— stationary with the flexible connection —a— wound thereon as by a pin and slot connection —j— between the cylinder —g— and shaft —h—. It will therefore be seen that with the present construction, a house of several floors, or a country home, without the use of a city water supply, may be installed with this apparatus and be found to operate in an efficient manner.

While the form of the invention herein shown and described is what is believed to be the preferred embodiment thereof, it is nevertheless to be understood that various forms, modifications and arrangements of the parts may be made without departing from the spirit and scope of the invention as claimed.

What we claim as new is:—

1. A well pump comprising a cylinder having a closed lower end, upwardly opening flap valves arranged in the lower end thereof, a piston slidably mounted in said cylinder, a piston rod carried by said piston, a rack bar fixed to the upper end of said piston rod, means carried by the upper end of said cylinder to limit the upward movement of the piston, a housing inclosing the upper end of said rack bar, guides for said rack bar carried by said housing, rollers carried by said housing in engagement with the rear face of said rack bar, spaced standards arranged within said housing, a pair of shafts arranged in said standards, a pinion upon each shaft in meshing engagement with each other, one of said pinions meshing with said rack bar, a bracket fixed to said housing, a tensioned rod slidably supported by said bracket, a toothed head carried by said rod adapted to engage the pinion that is free of connection with said rack bar, a stand pipe connected at its lower end to the lower end of said cylinder and extending outwardly of the housing at its upper end, the said piston adapted to descend by its own weight, and manually operated means associated with said meshing pinions for elevating said piston.

2. A well pump comprising a cylinder having a closed lower end, upwardly opening flap valves arranged in the lower end thereof, a piston slidably mounted in said cylinder, a piston rod carried by said piston, a rack bar fixed to the upper end of said piston rod, means carried by the upper end of said cylinder to limit the upward movement of the piston, a housing inclosing the upper end of said rack bar, guides for said rack bar carried by said housing, rollers carried by said housing in engagement with the rear face of said rack bar, spaced stand-

- ards arranged within said housing, a pair of shafts arranged in said standards, a pinion upon each shaft in meshing engagement with each other, one of said pinions 5 meshing with said rack bar, a bracket fixed to said housing, a tensioned rod slidably supported by said bracket, a toothed head carried by said rod adapted to engage the pinion that is free of connection with said 10 rack bar, a stand pipe connected at its lower end to the lower end of said cylinder and extending outwardly of the housing at its upper end, the said piston adapted to descend by its own weight, manually operated 15 means associated with said meshing pinions for elevating said piston, a plurality of distantly positioned operating members for disengaging the toothed head from said pinion, and means for holding the operating 20 members in adjusted position to permit the continuous descending movement of the piston.
3. A well pump comprising a cylinder having a closed lower end, upwardly opening flap valves carried by the lower end of 25 said cylinder, a piston vertically reciprocating in said cylinder, means carried by the cylinder for limiting the upward movement of the piston, a stand pipe connected at its lower end to said cylinder and adapted 30 to have its upper end spaced above a well, the said piston adapted by its own weight to force the water contained in the cylinder upwardly through the stand pipe, and manually operated means for elevating 35 the piston, the said means including a tensioned rod operatively associated therewith for locking the piston in any desired position.

In testimony whereof we affix our signatures. 40

STEPHEN PALHEGYI.
HERMAN EICHNER.
